D12-17. OR D 6,770 EX

DESIGN.

G. DELKER & C. L. BLONDIN.
Phaeton Bodies.

No. 6,770.

Patented July 8, 1873.

UNITED STATES PATENT OFFICE.

GEORGE DELKER AND CHARLES L. BLONDIN, OF HENDERSON, KENTUCKY.

DESIGN FOR PHAETON-BODIES.

Specification forming part of Design No. 6,770, dated July 8, 1873; application filed April 8, 1873.

To all whom it may concern:

Be it known that we, GEORGE DELKER and CHARLES LEON BLONDIN, of Henderson, in the county of Henderson and State of Kentucky, have invented a new Design for Phaeton-Bodies, of which the following is a specification:

Our invention relates to the contour of a flared seat, side panels, drop-rocker, and moldings, as hereinafter set forth.

The accompanying photographic view represents a phaeton-body illustrating our invention.

The phaeton-body is surmounted by a flaring-seat back, A, forming a graceful appearance in connection therewith. The side panel, B, is formed with an outline, substantially as

shown, and is ornamented with moldings a b c. C represents a downwardly-projecting drop-rocker, showing beneath the lower edge of the side panel.

The upwardly-projecting panel or back D is not an essential part of our design.

The following is claimed as new:

1. The ornamental design of the flaring seat A, side panel B, and moldings a b c, substantially as shown.
2. The outline of the drop-rocker C and panel B.

GEORGE DELKER.
CHAS. LEON BLONDIN.
